11 Claims. (Cl. 162—233)

The present invention relates to the digestion of cellulosic materials in alkaline cooking liquors, and more particularly to methods of and apparatus for retarding the corrosion of the inner face of a digester shell during one phase of the operating cycle.

In the pulp and paper industry wood chips are treated in digesters with a cooking liquor under controlled conditions of temperature, pressure, and time. The cooking liquid in the sulphate process of pulp production is predominantly composed of an aqueous solution of sodium hydroxide and sodium sulfide, and under digestion conditions dissolves the interfiber bonding materials of the wood whereby the fibrous material may be subsequently separated from the bonding materials which are in solution in the residual black liquor.

During recent years it has been observed that the corrosion rate of the inner face of the metal walls of the digester shells has been greatly accelerated in the sulphate digesting processes although when sulphides are absent, as in the soda digesting process, the corrosion problem has not experienced a corresponding change. The increase in corrosion has reduced the life of the digesters and greatly increased that portion of the cost chargeable to this element of the plant in the production of pulp and paper. The reason for the accelerated corrosion is unknown, but has occurred universally and has adversely affected the useful life of mild carbon steel, as well as alloyed steel, digester shells. Many attempts have been made to select a suitable alloy for installation in digesters to reduce or eliminate corrosion. Generally speaking, these attempts have not been successful, in that the increased life of the alloy metal has not justified the increased cost of the alloys.

One of the primary causes for the corrosion of digester shells is a direct or indirect result of the concentration of the liquor on the shell of a digester. Under operating procedures sufficient heat is stored in the shell of the digester to cause evaporation and concentration of cooking liquor contacting the digester shell in small quantities. Small quantities of liquor usually contact the hot walls of the digester as a result of splashing of the liquor stream during recharging of the digester and are concentrated by evaporation and apparently cause corrosive attack of the shell metal.

In accordance with the present invention we provide an inner liner spaced from the digester shell which is constructed and arranged for the accumulation of an insulating layer of pulp fibers between the liner and the shell. The heat barrier so formed restricts heat flow from the shell of the digester so that localized evaporation and concentration of incoming cooking liquor is avoided. The liner is constructed of relatively thin perforated plates or screens of low heat storage capacity which are spaced and supported from the inner surface of the digester shell. The liner is constructed for ease of installation, inspection and removal, and is so supported by the digester shell that relative movement between liner and shell, as caused by temperature difference, is accomplished without stressing the assembly.

2

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described an embodiment of our invention.

Of the drawings:

- 10 Fig. 1 is an elevation view of a pulp digester incorporating the liner of the present invention;
Fig. 2 is an enlarged view of a perforated panel liner section;
Fig. 3 is an end view of the panel liner taken on line 15 3—3 of Fig. 2;
Fig. 4 is an enlarged view of a portion of the panel liner and its supporting means shown in Fig. 3;
Fig. 5 is an enlarged plan view of the panel liner supporting means;
20 Fig. 6 is an exploded perspective view of the panel liner supporting means;
Fig. 7 is a section view taken on the line 7—7 of Fig. 5;
Fig. 8 is a section view taken on the line 8—8 of Fig. 2;
Fig. 9 is a section view taken on the line 9—9 of Fig. 8;
Fig. 10 is a plan view of a screen liner;
Fig. 11 is a section view taken on the line 11—11 of 30 Fig. 10; and
Fig. 12 is an elevation, in section of the upper portion of the digester shown in Fig. 1 arranged for the introduction of wood chips and cooking liquor.

While we illustrate one common type of stationary 35 pulp digester, it will be understood that other types of digesters, such as rotary digesters, are known and in use in this country and abroad. The present invention is applicable to all types of pulp digesters, and for purposes of illustration the liner shown is typical of the 40 construction involved.

As shown in Fig. 1, the shell 10 of the digester is 45 of circular cross-section having a domed top 11 and an inverted frusto-conical bottom portion 12. The dome 11 is provided with a central upper opening for the admission of wood chips and cooking liquor. As shown in Fig. 12, a hopper shaped charging spout 19 is inserted into the central opening 13 of the digester for the introduction of the wood chips, while the liquor enters through a nozzle 29 projecting through one wall of the spout. 50 The opening is provided with a cap member 14 which fits over the neck of the opening in pressure tight relationship therewith. In the embodiment shown, cooking temperatures and pressure within the digester are attained by the introduction of steam through a pipe 15 and a steam distributor coil 16 which is disposed in the lower portion 55 of the digester shell. The flow of steam to the digester is regulated by manipulation of the valves 17 and 18 in the pipe 15. The digester is provided with a pressure relief connection 29 located in the domed top 11, which 60 is used to reduce the pressure in the digester when the "cook" is completed. The bottom portion 12 is provided with an axially positioned outlet connected with a valved discharge pipe 21 for the discharge of the pulp and residual liquor from the digester at the end of the 65 "cooking" period.

In the customary procedure of operation the digester 70 is progressively filled with cooking liquor at a temperature of approximately 180 to 190° F. while simultaneously the wood chips are also being introduced into the digester. In the sulphate or kraft process, white liquor consisting of sodium hydroxide and sodium sulphide is utilized as the cooking liquor although it is sometimes

desirable to add a small amount of residual black liquor from a previous cooking cycle to the new "cook." The digester body is filled with wood chips and liquor to a level spaced below the top 11, and when this level is reached, the spout 19 removed and the digester is closed by the cap 14, and steam is supplied through the coil 16.

In some systems of digester operation the wood chips may be delivered to the digester before the liquor is introduced. Other units are operated with a small portion of the liquor charge being first introduced and thereafter the wood chips and liquor are simultaneously introduced until the digester is filled.

The delivery of steam to the filled digester displaces air which may be trapped in the submerged chips or present in the pores of the wood chips, as well as that which is present within the shell of the digester above the liquor level. During the displacement of the air by steam certain gases such as turpentine and acetone are liberated, with both the gas and the air discharged through the vent connection 20.

It is common practice to bring the pressure within the digester up to 120 to 130 p.s.i. and a temperature of from 340 to 350° F. in a period of from 1 to 2 hours. After the desired temperature and pressure conditions have been obtained the steam flow is reduced to a value sufficient to compensate for radiation losses, and the digester is maintained at the desired temperature and pressure condition for a cooking period of from 1 to 3 hours.

As illustrated in the drawing, the digester is arranged for the direct introduction of steam into the digester by means of the distributing coil 16. It will be understood that in some cases cooking pressure and temperature is obtained by the circulation of liquor from the digester through a heat exchanger wherein it is heated by steam and returned to the digester.

After maintaining the digester at the selected temperature and pressure for the desired period of time, the steam supply through pipe 15 is cut off and pressure is reduced by exhausting steam through the vent connection 20. Thereafter the discharge pipe 21 is opened and the contents of the digester discharged. This procedure ordinarily takes from 10 to 15 minutes and immediately thereafter the digester is available for recharging with liquor and chips, and the batch cooking process is repeated.

It is common knowledge that corrosion and erosion in pulping digesters is not uniform over the inner surface of the digester shell. Extensive inner surface areas of a digester shell may corrode at a high rate while other areas in the same vessel may show an inconsequential corrosion rate, or no corrosion at all. This condition also occurs generally regardless of the composition of metal used in constructing the digester shell. Generally, the shell areas showing no-corrosion or a low rate of corrosion are found to be covered with a scale consisting primarily of calcium carbonate.

We have found that one of the primary causes of digester corrosion is apparently the direct or indirect result of a localized increase in the concentration of the cooking liquor by evaporation from contact between relatively small amounts of cooking liquor and the hot shell of the digester. The temperature in the digester shell immediately following discharge of pulp therefrom will ordinarily approximate that of the cooking temperature, which is of the order of 340° F. During the recharging of the digester the entering cooking liquor has a tendency to splash upon, or to otherwise contact, the digester shell in small amounts. Under such circumstances the cooking liquor is heated and a portion thereof vaporized by the heat stored in the digester shell, with a resulting concentration of the liquor.

It will be noted that ordinarily a digester will be from 40 to 50 feet long, and 10 to 15 feet in diameter. With these dimensions and the customary operating pressure utilized in the digestion process, the digester shell will

be approximately 1 and $\frac{1}{4}$ " thick. This thickness of the shell provides an appreciable heat storage capacity, so that the shell 10 does not cool very rapidly by heat exchange to the atmosphere.

The excessive corrosion upon the heavy shell can be avoided by the installation of a shield or liner spaced from the inner surface of the digester. As shown in Figs. 2 to 9, the liner is disclosed in the form of a multiplicity of perforated plates, while in Figs. 10 and 11, the liner is disclosed in the form of a wire mesh screen. In each embodiment of the invention, the liner is provided with spacing means for maintaining the liner in positional relationship inwardly of the surface of the digester shell 10.

As shown in Figs. 1 to 4, inclusive, each perforated panel 22 is rectangular and dimensioned to allow passage of individual plates through access openings in the shell of the digester. The panels are desirably thin, for example $\frac{1}{8}$ inch, for low heat storage capacity and economical installation. For mounting purposes, the corners are cut out and the edges of the panels are bent to form flanges 23 which extend equally in a general perpendicular direction on one side of the panel 22. The panel is bent in the same direction as the flanges an amount equal to approximately one half the depth of the flanges 23, so as to generally follow the contour of the shell when installed.

Each panel is provided with a plurality of openings 24 therethrough which may be of the form shown in Figs. 2, 8, and 9. The number of the openings may be of any convenient number and size, depending upon the dimension of the individual plates 22. In the example shown, the panels 22 are approximately 12 by 18 inches, and the openings 24 are approximately 2 inches wide. The openings are made by slitting the panel, and displacing the metal in one direction on one side of the slit, while the metal is displaced in the opposite direction on the other side of the slit. With this construction each of the openings 24 lies in a plane generally normal to the surface of the panel, and is bounded by the edges of the plate portions oppositely displaced on the sides of the slit. The displaced portions of the plate form hoods 25 and 26 in the panel.

The panels 22 are mounted in the digester so that the hood 25 of each of the openings 24 is uppermost and projects inwardly toward the axis of the digester while the hood 26 of each opening is lowermost and projects toward the shell 10. Thus, the hood 26 extends partially into the space 27 between the panels 22 of the liner and the shell 10 of the digester. With this construction and arrangement the introduction of the wood chips and liquor into the digester will not cause gravity movement of chips into the space between the liner and the shell. However, as the level of cooking liquor and wood chips rises in the digester some liquor and chips will pass through the openings 24 into and accumulate within the space 27 between the liner and the shell.

The individual panels 22 of the liner are maintained in position by T-bars 30 which are spot welded to the shell 10 and are circumferentially spaced in axially extending parallel rows so that the edges and flanges 23 of the panels are held by the cross-bars 31 of the T-bars. In the embodiment of the invention illustrated, the panels 22 are installed in longitudinal rows in the digester with adjacent panels in each row abutting each other. Each row of panels 22 is positioned longitudinally in the digester by upper and lower cap members 32 which are spot welded to the T-bars. The spacing between adjacent bars 30 is such that the panels 22 fit loosely therebetween so that differential expansion of the liner and the shell will neither bind nor permit the panels to fall out of position during operation of the digester.

The T-bars 30 are constructed in sections with a tongue and groove joint therebetween, as illustrated in Figs. 2, 5, 6, and 7. The groove 33 in one end of a cross-bar 31 engages a matching tongue 34 on the end

of an adjacent T-bar 30. Referring particularly to Fig. 6, it will be noted the leg 35 of the end of one T-bar is cut back so that the grooved cross-bar 31 extends beyond the end of the leg while the leg 35 of the matching end of the adjacent T-bar is extended beyond the tongue 34. As shown, the leg 35 of the T-bar 30 is spot welded to the shell 10 at one end portion thereof, as at 36, so that the opposite end of each T-bar section is free to move longitudinally in the tongue and groove joint in accordance with temperature changes occurring during operation of the digester.

The liner shown in Figs. 10 and 11 includes a screen formed from comparatively light gauge wire 37 having, for example, $\frac{1}{4}$ inch openings 38. The screen may be of one piece construction to line the shell of the digester or may be made in sections with adjoining sections installed in abutting relationship internally of the digester shell. The size of screen section is determined by the size of the access openings in the digester shell.

The screen is mounted in a spaced position inwardly of the shell 10 by means of circumferentially and longitudinally spaced supporting means. In the embodiment, the supporting means consists of a length of pipe 40 which is welded at one end to the inner surface of the shell 10 and projects in a general radial direction toward the longitudinal axis of the digester. A collar is constructed from a piece of pipe 41 having an internal diameter greater than the external diameter of, and having a lesser length than, the pipe 40. A washer 42 having a central opening 43 therethrough of a diameter greater than the external diameter of the pipe 40 is welded to one end of the pipe 41. The assembly of pipe 41 and washer 42 is inserted over the pipe 40, with the washer 42 spaced from the shell 10. The wires 37 of the screen are displaced as necessary to fit over the pipe 40, and the screen held against the washer 42 by a second washer 44 which is held in place by a rod member 45 which is inserted through a hole 46 drilled through the end portion of the pipe 40. The rod member 45 is bent to maintain its holding position in the pipe 40. With the structure described the screen is maintained in a spaced position inwardly of the digester shell 10. The circumferential and longitudinal spacing of the pipes 40 is sufficient to maintain the screen liner away from the shell 10 to provide a space 27' therebetween similar to the space 27 between the panels 22 and shell 10 shown in Figs. 9 and 10.

In the operation of a digester equipped with the liners described, a mat of pulp fibers is trapped in the space 27 (or 27') which serves as an insulating blanket which not only prevents splashing liquor from directly contacting the shell 10 of the digester but also permits the liner to release heat at the end of a cooling cycle so that the heat storage therein is not sufficient to cause the surface boiling and corrosion conditions described. At the end of the pulp cooking period the pulp fibers in the space 27 are saturated with liquor, and when the digester is pressure relieved during blow-down some of the liquor in the fibers flashes to a vapor by the pressure reduction. The stored heat in the relatively thin liner is transferred to the liquor discharged from the digester, resulting in lowering the temperature of the liner to a temperature of the order of 220° F. The fibers accumulated in space 27 also serve as an insulation to prevent regain of heat in the liner from the shell during the recharging of the digester. With the substantial elimination of surface boiling conditions, corrosion resulting from localized concentrations of cooking liquor is greatly retarded, if not avoided. We have found that the liner, whether in the form of perforated panels or a screen, can be constructed of mild steel without serious corrosion difficulties, even though corrosion of alloy metal shells had occurred in the same digester prior to the installation of the liners of the present invention.

As disclosed and claimed in copending applications of

R. H. Richter digester corrosion can be retarded by cooling the shell of the digester to a temperature of the order of 220° F. by heat exchange with a heat transfer medium, Serial No. 334,132, filed January 30, 1953; and by the introduction of the cooking liquor into the lower end portion of the digester so as to form a quiescent pool with a gradually increasing level until the digester has been filled, Serial No. 334,134, filed January 30, 1953. In both applications localized concentration of the liquor by evaporation from surface or hot face boiling is avoided.

While in accordance with the provisions of the statutes we have illustrated and described herein the best forms and mode of operation of the invention now known to us, those skilled in the art will understand that changes may be made in the form of the apparatus disclosed without departing from the spirit of the invention covered by our claims, and that certain features of our invention may sometimes be used to advantage without a corresponding use of other features.

What is claimed is:

1. In a digester, metallic walls defining an elongated body having valved inlet and outlet openings therein for the admission of wood chips and cooking liquor and for the discharge of pulp, and means for accumulating a layer of heat insulating pulp fibers adjacent the inner surface of said metallic walls comprising metallic liner means inwardly spaced from said digester walls, said liner means including rows of perforated panels having flanged edges, and T-bar spacer means attached to the walls of said digester and overlaying the edges of said panels.
2. In a digester, metallic walls defining an elongated body of circular section having valved inlet and outlet openings therein for the admission of wood chips and cooking liquor and for the discharge of pulp, and means for accumulating a layer of heat insulating pulp fibers adjacent the inner surface of said metallic walls comprising an inner metallic liner means having flanged edges spaced from said digester walls, said liner means including rows of perforated panels, and rows of circumferentially spaced T-bars extending longitudinally of the walls of said digester for positioning said panels.
3. In a digester, metallic walls defining a pressure vessel having valved inlet and outlet openings therein for the admission of cellulosic material and cooking liquor and for the discharge of pulp, and means for accumulating a layer of heat insulating pulp fibers adjacent the inner surface of said metallic walls comprising liner means positioned internally of said vessel walls comprising rows of perforated panels having edges turned toward said walls, and T-bar members spot welded to the inner surface of said walls and arranged in overlaying relationship to the edge surfaces of said rows of panels.
4. In a digester, metallic walls defining an upright cylindrical pressure vessel having valved inlet and outlet openings therein for the admission of wood chips and cooking liquor thereto and for the discharge of pulp therefrom, and means for accumulating a layer of heat insulating pulp fibers adjacent the inner surface of said metallic walls comprising metallic panels spaced inwardly of said digester walls of said pressure vessel, said panels having upwardly opening hooded openings therethrough for the movement of pulp therethrough into the space between said panels and said pressure vessel walls.
5. In a digester, metallic walls defining a pressure vessel having valved inlet and outlet openings therein for the admission of cellulosic material and cooking liquor thereto and for the discharge of pulp therefrom, means for accumulating a layer of heat insulating pulp fibers adjacent the inner surface of said metallic walls comprising liner means spaced from the internal surface of said digester walls, said liner means comprising a plurality of perforated panels having flanged edges, and spacing means for said panels comprising parallel rows of T-bars, each row formed in sections with one end portion of each section welded to the inner surface of said digester

wall and connected with an adjoining section by a tongue and groove joint.

6. A digester for the preparation of pulp by the batch digestion of cellulosic materials in a cooking liquor comprising metallic walls having a relatively high heat storage capacity defining a digester body, means forming a valved inlet and a valved outlet in said metallic digester walls for the admission of cellulosic materials and cooking liquor to and for the discharge of pulp from said digester, and means for accumulating a layer of heat insulating pulp fibers adjacent the inner surface of said digester walls comprising a liner spaced and supported from the inner surface of said digester walls, said liner having openings therein of sufficient size for movement of cellulosic materials and cooking liquor therethrough.

7. A digester for the preparation of pulp by the batch digestion of cellulosic materials in a cooking liquor comprising metallic walls having a relatively high heat storage capacity defining a digester body, means forming a valved inlet and a valved outlet in said metallic digester walls for the admission of cellulosic materials and cooking liquor to and for the discharge of pulp from said digester, and means for accumulating a layer of heat insulating pulp fibers adjacent the inner surface of said digester walls comprising a metallic liner of relatively low heat storage capacity having openings therein of sufficient size for movement of cellulosic materials and cooking liquor therethrough, and a plurality of laterally spaced supports for locating said liner at a spaced position internally of said digester walls.

8. A digester as defined in claim 6 wherein said liner comprises a plurality of individually supported perforated panels.

9. A digester as defined in claim 7 wherein said liner comprises a wire mesh screen.

10. A digester as defined in claim 6 wherein said liner comprises a wire mesh screen, a plurality of longitudinally and circumferentially spaced members attached to and projecting inwardly of the walls of said pressure vessel, a first washer associated with said member and spaced from said wall to position said screen, and a second washer positioned to retain said screen on said first washer.

11. A digester as defined in claim 6 wherein said liner comprises a wire mesh screen, a plurality of longitudinally and circumferentially spaced members welded to the inner surface of said walls and projecting inwardly of said pressure vessel, a first washer associated with said member and spaced from said wall to position said screen, and a second washer associated with said member and positioned to retain said screen on said first washer.
